C. C. Shepherd.

ATTORNEY

UNITED STATES PATENT OFFICE.

HANNIBAL D. FIELDS, OF COLUMBUS, OHIO.

BAND-SAW GUIDE.

SPECIFICATION forming part of Letters Patent No. 411,241, dated September 17, 1889.

Application filed February 9, 1889. Serial No. 299,351. (No model.)

To all whom it may concern:

Be it known that I, HANNIBAL D. FIELDS, a citizen of the United States, residing at Columbus, in the county of Franklin and 5 State of Ohio, have invented a certain new and useful Improvement in Band-Saw Guides, of which the following is a specification.

My invention relates to the improvement of guides or adjusters for band-saws.

10 The objects of my invention are to provide guide-blocks for band-saws so supported and arranged as to admit of the saw being held in proper cutting position; to provide for the uniform adjustment of the cutting portion of the saw by the operation of but one lever; to admit of the saw being adjusted for cutting in the desired direction while the same is running; to provide for the extension or shortening of the rods connecting said guides with 15 the lever-shaft; to provide one of said guides with a frictional roller, against which the rear edge of the saw may bear, and to so connect said roller and guide-block as to admit of the former being removed without the necessity 20 of taking the guide apart; to provide means for regulating the distance between said guide-blocks and the outer end of the column-arms which support them; to provide for the vertical adjustment of said blocks and their 25 supporting-arms, and to provide said guide-blocks with saw-bearing guide-strips adjustable for use with saws of different widths. These objects I accomplish in the manner 30 illustrated in the accompanying drawings, in 35 which—

Figure 1 is a view in perspective of my improved device. Fig. 2 is a face view of a portion of the frame-column, taken on line xx of Fig. 1. Fig. 3 is a sectional view of the turn-buckle connection of the guide-operating arms. Fig. 4 is a plan view of one of the 40 guide-blocks. Fig. 5 is a view of the rear face of one of said guide-blocks. Fig. 6 is a sectional view taken on line yy of Fig. 5. Fig. 45 7 is an end elevation of one of said guides, and Fig. 8 is a rear face view of one of the end plates of one of the guide-supporting arms.

Similar letters refer to similar parts throughout the several views.

A represents a vertical post or saw-column

provided on its outer face with a central vertical projection or cleat a , the latter having its vertical edges beveled inwardly in the form of a dovetail, as shown.

55

B represents two parallel arms made to project horizontally outward, one above the other, from that face of the column A having the cleat a , the rear ends of said arms being provided with dovetailed grooves, through which 60 passes loosely the correspondingly-shaped cleat a of the column A, thus supporting said arms B at right angles with said column. The outer end of each of these arms B is provided, as shown, with a fixed oblong plate b , of such 65 length as to project outwardly a short distance from the front face of said arms. This outwardly-projecting end of each of the plates b is shaped to form, as shown, a dovetailed tongue b' .

70

C represents the lower saw-guide block, consisting of two parallel plates c , having their inner faces supported a short distance apart and connected by transverse screw-threaded bolts c' , the slotted heads of which 75 are flush with the outer surface of the outer plate c . These bolts c' are provided, as shown, between the plate c with nuts c^2 , made to bear, respectively, against the inner faces of said plates c . The inner plate c is provided at the 80 center of its height and in rear of the center of its length with a horizontal slot D, the inner termination of which is somewhat enlarged.

75

d represents an approximately-square frame 85 having the outer surface of its upper and lower sides beveled, and having extending transversely therethrough in its lower half and projecting outwardly therefrom a fixed half of a bearing-box d' , the latter having a 90 horizontal and central bearing-groove in its upper surface, as shown. A small frictional wheel e , pivotally mounted on the inner end of a short shaft e' , being first introduced between the plates c through the enlarged end 95 of the slot D, the frame d is then so held that one of the projecting ends of the half bearing-box d' extends into the outer end of the slot D. The frame may then be moved against the face of the plate c until said inwardly-projecting end of the half-box d' is within 100 the enlarged inner end of the slot D and the

beveled upper and lower edges of the frame have been made to slide beneath the beveled overhanging edges of two short cleats d^2 , respectively secured above and below the enlarged end of the slot D. The outer end of the shaft e' having been made to bear in the groove of the lower half-box d', the loose upper half d^3 is inserted within the frame and secured by screws or bolts f upon the fixed lower half of the box, thus providing a bearing for the shaft of the friction-wheel. Made to project outwardly from one side of the frame d is a short arm f'.

F represents an oblong plate detachably secured by screws or otherwise in a vertical position to the outer face of said inner plate c at a point near its rear end, said plate F having projecting outwardly therefrom in a position parallel with the arm f' an arm g. These arms g and f' are provided with oppositely-located screw-holes, through which are made to pass and adjustably connect said arms a screw g'.

H represents vertical saw-bearing strips, of which there are preferably two pairs, the strips of each pair being oppositely located and being supported, respectively, against the inner sides of the plates c by means of binding-strips h, one of which is secured to each of the upper sides or edges of the plates c by means of set-screws h' and made to clamp the upper outwardly-bent ends of the strips H against the upper sides of the plates c.

Between lugs I, made to project from the outer side of the inner plate c of the guide-block, is pivoted a short block i, having formed on its rear side a dovetailed groove. Into this groove is made to fit and slide the tongue b' of the outer end of the plate b, thus connecting the guide-block C with the arm B. Secured to the under side of the sliding block i is one end of a metallic strip k, which, extending downwardly and thence rearwardly to a point beneath the end plate b, is connected at its outer end with a short downwardly-projecting arm b² on the under side of the plate b by a horizontal screw-threaded pin k', said pin being made to engage with the internal screw-threads of oppositely-located screw-holes formed in said arms k and b². The backward and forward movement of the block i is limited by a slot j, formed therein, through which projects a pin or bolt j', made to extend outwardly from the front end of the plate b.

Although the above-described guide-block is that connected with the lower supporting-arm b, it will be observed from the drawings that the description of the said lower guide-block and its connection with the lower supporting-arm B is also applicable to the upper guide-block C and its connection with the upper arm B, except that the roller e and the means for inserting and supporting the same are omitted from the upper block.

Projecting outwardly from the column A at a point near its upper end and on that side

corresponding to the side from which the cleat a projects is a bracket L. Pivotally supported between this bracket L and the floor is a vertical shaft l, preferably square in cross-section, as shown. Loosely mounted on this shaft l is a short outwardly-projecting arm M, having its outer end slotted, as shown. This arm M is supported at a point slightly above the upper arm B by means of a short rod m, one end of which is secured to the upper side of the arm B at or near the inner end thereof. The remaining end of the rod m is secured to a boss formed on the under side of the arm M, thus holding the arm M in connection with the upper arm B.

N' represent short rods, through which a connection is formed between the shaft-arm M and the upper guide-block C. The rod N has one of its ends pivoted within the slotted end of the arm M, and has its remaining screw-threaded end entering one end of a larger internally-screw-threaded tube or turn-buckle n. The rod N' has a similar connection with the remaining end of the turn-buckle and extends outward to the guide-block, having its outer end pivotally connected with the rear plate c thereof.

M' represents an arm corresponding with the arm M, and which is secured and connected with the lower arm B and lower guide C in the manner prescribed for said arm M, the same letters of reference being employed to indicate corresponding parts.

P represents a lever having one of its ends fixed on the shaft l at a point between the arms M. Loosely embracing this lever are the two parallel and notched arms of a lever stop-bar q, one end of which is secured to the side of the column A. The lever P is provided on one side with the usual form of a spring-actuated lever-locking rod r, having a bolt s on one end adapted to rest within one of the notches of the bar q and to be withdrawn therefrom in the usual manner by pressure on the handle r'. The lower supporting-arm B is preferably assured in its position against the cleat a by a set-screw a'. While the upper arm B may be similarly connected it is obvious that other means may be employed for supporting the arms at the desired height.

The operation of the above-described device is as follows: The saw S, which is mounted upon pivoted wheels in the usual manner, is made to pass vertically downward, as shown, between the front or bearing portions of the guide-plates c, the guide-strips H being so set as to bear loosely against the flat faces of said saw while the rear edge of the saw has a bearing against the frictional roller e, pivotally supported, as described, in the lower guide-block C. It will be observed that by loosening the nuts c² of the screw-threaded bolts c' and turning the latter the distance between the plates c may be increased or diminished to accommodate a thicker or thinner saw-blade. The lateral adjustment of

the saw-guides may be effected by turning the screws k' , which will operate through the arm k to force the grooved blocks i outward or inward upon the outer and thickened end of the end plates b , and by turning the turn-buckle couplings n of the rod N N' to increase or diminish the length of the connection between the shaft-arms and guide-blocks. As will be seen, the distance between the upper and lower guide-blocks may be regulated as desired by raising or lowering either or both of the arms B upon their support a . When it is desired to change the angle at which the saw-blade stands, a uniform adjustment thereof may be had at the upper and lower guide-blocks by an outward or inward pressure upon the lever P , the latter being fixed in its position by allowing the bolt s of the locking-rod r to drop into the desired notch of the bar q . This uniform adjustment is attained through the shaft l , arms M , connected therewith, and the above-described connections between said arms M and guide-blocks C . It will be observed that in raising and lowering the arms B the arms M are carried upward with said arms B through the connection therewith of the rods m . In case it should become necessary to remove the bearing-wheel e it may be accomplished without the necessity of taking apart the lower guide by removing the screw g' , disconnecting the upper half of the bearing-box d^3 and drawing the frame d outward from its bearing in the cleat d^2 , thus admitting of the

roller e being drawn outward through the enlarged end of the slot D . 35

Having now fully described my invention, what I claim, and desire to secure by Letters Patent, is—

1. In a band-saw guide, the combination, 40 with a supporting-arm B , projecting from a column, of the connected guide-block plates c , friction-roller e , pivoted between said plates, saw-bearing strips H , having their upper bent ends adjustably clamped, as described, by 45 strips h against the upper side of said plates c , the rear plate c being adjustably connected, as described, with said arm B , substantially as and for the purpose set forth.

2. In a saw-guide, the combination, with the 50 connected plates c , of the guide-block C , one of said plates c having a slot D , provided with an enlarged inner end, cleats d^2 above and below said enlargement, and plate F , having outwardly-projecting arm g , said plate being 55 detachably secured to said plate c of the frame d , having half-bearing box d^3 and projecting arm f' , bearing-box cap d^5 , detachably secured on said half-bearing box and forming in connection therewith a bearing for shaft e' 60 of wheel e , and screw g' , connecting said arms g and f' , substantially as and for the purpose specified.

HANNIBAL D. FIELDS.
